WATER SOLUBLE BRIGHTENER COMPOSITION

Robert Sidney Long, Bound Brook, and Julian Jacob Leavitt, Plainfield, N. J., assignors to American Cyanamid Company, New York, N. Y., a corporation of Maine

No Drawing. Application May 6, 1955
Serial No. 506,664

10 Claims. (Cl. 252—301.2)

This invention relates to optical bleaching agent compositions and to a process for the preparation thereof. More particularly it relates to optical bleaching agent compositions comprising an inorganic salt of a coumarin type bleaching agent and an organic acid of the group consisting of maleic, fumaric, oxalic, tartaric and benzene phosphonic acids.

Compounds of the 7-amino coumarin type are known for their optical bleaching agent properties, producing a whitening or brightening effect on various fabrics by the emission of blue fluorescence to compensate for the natural yellowing of the cloth. The compositions including brighteners of the coumarin type, described above, are especially useful on certain types of fibers and fabrics for this purpose. One important application of these is in a step in the processing of fabrics such as wool, acetate, nylon, etc., whereby a brighter, whiter appearance is imparted to the cloth. In such applications the bleaching agent is applied to the fabric from an acidic aqueous bath. The optical bleaching agents, as prepared, are, however, not water soluble and it is therefore necessary for the operator first to dissolve the agent in an organic solvent or in a strong mineral acid such as sulfuric acid and then add this solution to the bath in preparation for the process treatment. If the aqueous solubility of the agent could be improved, this pre-solution step could be avoided.

Various attempts have been made to produce easily water soluble coumarin brightening agents by insertion of various solubilizing groups. In the coumarin molecule, however, this does not produce satisfactory results since the products generally show inferior optical bleaching properties. The coumarin compounds containing amino groups form salts with strong inorganic acids soluble in water, but these are not suitable since there is a strong tendency to hydrolysis in the bath with the precipitation of the coumarin compounds. This is especially true on further dilution of the solution, thus interfering with the bleaching effect.

Some of the coumarin brighteners have been mixed with various solid inorganic compounds to make water soluble compositions. Such mixtures have been found to be quite hygroscopic. Even when deliquescence is not observed, there is caking from absorption of water from the air. Since brighteners are used in plants whose atmosphere is highly humid, such as defect is a serious disadvantage.

We have found that optical bleaching agent compositions prepared by mixing a strong inorganic acid salt of a coumarin type of bleaching agent with certain organic acids show good water solubility, avoiding hydrolysis and precipitation of the coumarin compound upon further dilution of the bath in which they are used. Furthermore, the compositions are resistant to absorption or taking up of moisture from the atmosphere to the extent that the tendency for caking and formation of wet sticky products upon atmospheric exposure is greatly diminished in many cases.

2

Coumarin derivatives suitable for the optical bleaching compositions of this invention may be represented by the formula:

where X is an alkyl group such as methyl or ethyl and Y is hydrogen, alkyl or alkenyl, and where X and Y may be joined to form a polymethylene chain. As examples of the coumarins suitable may be mentioned 4-methyl-7-diethylaminocoumarin, 3,4-tetramethylene-7-diethylaminocoumarin, and the like. A particularly preferred species, however, is 4-methyl-7-diethylaminocoumarin. These are used in the form of a strong inorganic acid salt such as the sulfate, chloride, phosphate, nitrate, etc. We particularly prefer, however, to use the sulfate because of its ease of preparation.

The acids which can be satisfactorily used in our invention are a group of relatively cheap available organic acids, namely, oxalic, maleic, fumaric, tartaric, and benzene phosphonic acids. The choice of these acids over the many other possibilities among acid compounds is not governed by acidity. Other acids of about the same acidity (e. g. malonic or citric) are not usable because their mixtures with the coumarin brightener salts cake up as do the mixtures with acidic inorganic compounds. Consequently, our invention is limited to the use of these specific acids.

Various proportions of the acidic ingredient may be used in our compositions from about 2.5 to about 15 parts with one part of the coumarin salt (calculated as the base). However, we prefer to use from about 3.5 to 9 parts.

In preparing the bleaching agent compositions of our invention the coumarin derivative is first converted to the inorganic acid salt. This is accomplished by dissolving the coumarin derivative in an aqueous solution of the inorganic acid of sufficient concentration to cause easy solution. The inorganic acid salt is then isolated by ordinary methods, such as salting out by addition of the sodium salt of the corresponding acid. The coumarin salt is then admixed with the acid ingredient by ordinary mixing, grinding the two together, treatment in a ball mill, or similar operations. A dry powdery product is thus obtained.

The optical bleaching compositions are useful for brightening fabrics of protein fibers such as wool and silk, superpolyamide fibers such as Nylon, acetate rayons, etc. They may be added directly to the bath for fabric treatment from a concentrated aqueous stock solution without resulting in precipitation of the coumarin compound. In addition, the compositions may be used in other applications where the coumarin type of bleaching agent effect is desired.

The presence of the organic acid results in a product which is easily soluble in water and leaves no oily film. Furthermore, no precipitation takes place on extreme dilution of the bath. The acid ingredient evidently has a solubilizing effect and helps maintain the coumarin compound in solution.

The invention may be illustrated by the following examples in which parts are by weight unless otherwise specified.

Example 1

To 1000 parts of 20% by weight aqueous sulfuric acid at 60° C. is added 70 parts of 4-methyl-7-diethylamino-

coumarin with stirring. To the solution which forms there is added 300 parts of anhydrous sodium sulfate. The stirring is continued without the application of heat until the mixture reaches room temperature. The solid sulfate salt of the coumarin derivative is then removed by filtration and dried.

155 parts of sulfate (98.4 parts of coumarin base) is then blended with 845 parts of tartaric acid by grinding the acid with the sulfate salt. The resulting powder maintains a dry appearance when exposed to a humid atmosphere and dissolves readily in water leaving no oily film on the surface or any insoluble matter. It does not cake on standing. The blend contains 8.6 parts of the acid per part of the coumarin brightener, calculated as the base.

Example 2

The procedure of Example 1 is followed except that 358 parts of oxalic acid are used in place of the tartaric acid. The resulting powdery product maintains a dry appearance and a powdery form when exposed to a humid atmosphere and dissolves easily in water leaving neither oily film on the surface nor any insoluble matter. It does not cake on standing. The blend contains 3.6 parts of the acid per part of brightener, calculated as the free base.

Example 3

The procedure of Example 1 is followed except that benzene-phosphonic acid ($C_6H_5-PO(OH)_2$) is used in place of tartaric acid. The resulting powder composition dissolves readily in water.

Example 4

The sulfate salt is prepared as in Example 1. The sulfate is then blended with 1270 parts of tartaric acid. The resulting mixture dissolves easily in water. The blend contains about 13 parts of acid per part of coumarin base.

Example 5

The procedure of Example 1 is followed except that maleic acid is used in place of tartaric acid. The resultant mixture dissolves readily and completely in water. It does not cake on standing even in high humidity.

Example 6

The procedure of Example 1 is followed except that 3-allyl-4-methyl-7-diethylaminocoumarin is used in place of the 4-methyl-7-diethylaminocoumarin. The product is readily soluble in water and does not cake on standing.

Example 7

The procedure of Example 1 is followed except that

3,4-tetramethylene-7-diethylaminocoumarin is used in place of 4-methyl-7-diethylaminocoumarin, with similar effectiveness.

Example 8

The procedure of Example 1 is followed except that 3,4-trimethylene-7-diethylaminocoumarin is used in place of 4-methyl-7-diethylaminocoumarin. A similar product is obtained.

10 We claim:

1. A solid optical bleaching composition comprising a mixture of 1 part, calculated on the free base, of a strong inorganic acid salt of an optical bleaching agent of the formula:

15

wherein R_1 and R_2 are selected from the group consisting of hydrogen, lower alkyl, lower alkenyl, and a jointly formed trimethylene bridge, with from 3 to 15 parts of an organic acid selected from the group consisting of oxalic, maleic, fumaric, tartaric, and benzene phosphonic acids, characterized by the property of long storability in a humid atmosphere.

20 2. The compositions of claim 1 in which the sulfate of the optical bleaching agent is used.

3. The compositions of claim 1 in which the chloride of the optical bleaching agent is used.

4. The compositions of claim 1 in which the optical bleaching agent is 4-methyl-7-diethylaminocoumarin.

35 5. The compositions of claim 2 in which the optical bleaching agent is 4-methyl-7-diethylaminocoumarin.

6. The composition of claim 5 in which the organic acid is oxalic acid.

7. The composition of claim 5 in which the organic acid is fumaric acid.

40 8. The composition of claim 5 in which the organic acid is maleic acid.

9. The composition of claim 5 in which the organic acid is tartaric acid.

45 10. The composition of claim 5 in which the organic acid is benzenephosphonic acid.
